Primary Examiner — Michelle E. Wilson*Assistant Examiner* — Richard E Yenchesky(74) *Attorney, Agent, or Firm* — Tucker Ellis LLP(57) **CLAIM**

The ornamental design for a coating material container, as shown and described.

DESCRIPTION

FIG. 1 is a top perspective view of an embodiment of a coating material container showing a new design;
FIG. 2 is a bottom perspective view of the coating material container illustrated in FIG. 1.

FIG. 3 is a front view of the coating material container illustrated in FIG. 1;

FIG. 4 is a rear view of the coating material container illustrated in FIG. 1;

FIG. 5 is a left side view of the coating material container illustrated in FIG. 1;

FIG. 6 is a right side view of the coating material container illustrated in FIG. 1;

FIG. 7 is a top view of the coating material container illustrated in FIG. 1; and,

FIG. 8 is a bottom view of the coating material container illustrated in FIG. 1.

The broken lines show portions of the design that form no part of the claimed design.
